CUFF LINK

Olof V. Anderson, Cowesett, R. I., assignor to
 Anson Incorporated, a corporation of Rhode
 Island

Application October 12, 1949, Serial No. 120,835

2 Claims. (Cl. 24—97)

1

The present invention relates to cuff links and has particular reference to a novel construction therefor.

The principal object of the invention is to provide a cuff link which has a mounting post adapted to extend through the button holes of a cuff, and an ornamental head extending over the sides of the cuff.

Another object of the invention is to provide a cuff link having an ornamental head in the shape of a V.

A further object of the invention is to provide a cuff link having an ornamental head of V shape and a center post swingingly secured to one end of the head and selectively movable to positions spaced from the other end of the head and adjacent thereto.

In the drawings,

Fig. 1 is a perspective view of one embodiment of the novel cuff link;

Fig. 2 is a side view thereof, the parts being in closed relation;

Fig. 3 is a view similar to Fig. 2, the parts being in open relation;

Fig. 4 is an enlarged sectional detail of Fig. 3;

Fig. 5 is an enlarged section on the line 5—5 of Fig. 3; and

Fig. 6 is an exploded view of the cuff link parts.

It has been found desirable to provide a cuff link which has a post adapted to be passed through the button holes of a cuff, and an ornamental head of V-shape which is hingedly secured to one end of the post and is selectively movable to open and closed position with respect to the post, the post having a movable retainer head at its other end adapted to be selectively moved in parallel relation to the post in transverse relation thereto.

Referring to the drawings, the cuff link 10 includes an ornamental head 11, a post 12 hingedly mounted at one end to one end of the ornamental head, and a retainer head 13 swingingly mounted at the other end of the post.

The ornamental head 11 is of V shape, and is made of wire or flat stock as desired, one end 14 having a seat 15 secured to the inner surface thereof, as by soldering, the seat 15 having a bottom 16, ends 17, 18, and upstanding sides 19, 20 which have aligned pivot pin openings 21, 22 therethrough. The post 12 is of generally V shape, and is made of wire or flat stock, with two parallel arms 23, 24 and a V shaped lower end 25 in which a pivot block 26 is mounted, the pivot block 26 having a pivot pin opening 27 therethrough.

A flat spring 28 is seated in the seat 15 with its

ends engaging the ends 17, 18 of the seat, the spring being somewhat longer than the base to arch over the bottom 16; when the post 12 is positioned between the sides 19, 20 of the seat and a pivot pin 29 is passed through the openings 21, 22 and 27 and is headed over, the portions 30, 31 of the V shaped lower end 25 of the post selectively engage and press upon the spring 28 to releasably hold the post in two positions relative to the ornamental head, as shown in Figs. 2 and 3, whereby the ornamental head can be moved to closed or open position as illustrated, with respect to the post.

Referring now to Fig. 6, one arm 24 of the post 12 is recessed on its upper inner surface as indicated at 32, the sides 33, 34 of the recessed portion being bevelled. The retainer head 13, which is hollow and preferably made of tubular metal stock, has its ends closed, as by ornaments 35, 36, and has an opening 37 in one side, preferably square, to slidably receive a block 38 which has corner projections or cams 39. The upper ends of the post arms have aligned pivot pin openings 40, 41, the block 38 has a pivot pin opening 42, and the side of the head opposite the opening 37 has a pivot opening 43, see Fig. 5, whereby a pivot pin 44 is extended through the openings 40, 43, a spring 45, the opening 37, and the opening 41 and is headed over, see Fig. 5, to assemble the parts together. The rear face of the block 38 is recessed as indicated at 46 to seat the associated spring end therein.

When the retainer head is turned with respect to the post, the cams 39 are pressed in by bevelled sides 33, 34 and the block moves in against the spring 45 to permit the retainer head to rotate 90 degrees, whereupon the cams 39 snap out over the bevelled sides 33, 34 to releasably lock the retainer head with respect to the post. The retainer head is thus selectively movable to be resiliently held in parallel and in right angled relation to the post.

The cuff link is mounted on a cuff by moving the retainer head into parallel relation to the post, then passing the retainer head and the post through the cuff button holes, the link being open as in Fig. 3 to permit passage of the ornamental head over the cuff edges. The ornamental head is now swung over to seat the free end of the ornamental end against the post and thus close the cuff link, as in Fig. 2, and the retainer head is swung over, see Fig. 1, to releasably lock the cuff link in place on the cuff.

Although I have described a specific constructional embodiment of my invention, it is obvious

that changes in the size, shape, material, ornamentation, and relation of the parts may be made to suit requirements for different cuff link designs, without departing from the spirit and the scope of the invention as defined in the appended claims.

I claim:

1. In a cuff link, an ornamental head having two angularly positioned portions in V shape, a pivot seat at the outer end of one portion, a post pivotally mounted in said seat and having spaced parallel arms and a lower portion with angularly positioned surfaces, said pivot seat having a flat spring mounted therein, said angularly positioned surfaces being selectively engageable with said flat spring to releasably retain said post in spaced relation and in contact relation with the outer end of the second ornamental head portion, and a retainer head pivotally mounted between said post arms at the outer end thereof, said post being pivoted in the same plane as the V-shaped cuff link and said retainer head being pivoted between the arms of the post in a plane at right angles thereto.

2. In a cuff link, an ornamental head having two angularly positioned portions in V shape, a pivot seat at the outer end of one portion, a post pivotally mounted in said seat and having spaced parallel arms and a lower portion with angularly positioned surfaces, said pivot seat having a flat spring mounted therein, said angularly positioned

surfaces being selectively engageable with said flat spring to releasably retain said post in spaced relation and in contact relation with the outer end of the second ornamental head portion, a retainer head pivotally mounted between said post arms at the outer end thereof and spring means for releasably selectively retaining said retainer head in alignment with the post and at right angles thereto said post being pivoted in the same plane as the V-shaped cuff link and said retainer head being pivoted between the arms of the post in a plane at right angles thereto.

OLOF V. ANDERSON.
